FRICITION WELDING MACHINE

James H. Edwards, Newtown, Conn., assignor to American Machine & Foundry Company, a corporation of New Jersey

Filed Oct. 2, 1963, Ser. No. 76,837

Term of patent 14 years

(Cl. D26—1)

FIG. 1

FIG. 2

Des. 203,177

PAGE 3

FIG. 3

FIG. 4

FIG. 1 is a front perspective view of a friction welding machine showing my new design, in horizontal position;

FIG. 2 is a rear perspective view thereof;

FIG. 3 is a view similar to FIG. 1 but showing the machine in vertical position, the end-support brace being removed therefrom; and

FIG. 4 is a rear perspective view thereof.

I claim:

The ornamental design for a friction welding machine as shown.
